US0D1097674S

(12) United States Design Patent (10) Patent No.: US D1,097,674 S
(45) Date of Patent: * Oct. 14, 2025

(54) OVEN

- (71) Applicant: Samsung Electronics Co., Ltd., Suwon-si (KR)
- (72) Inventor: Jang-Won Kim, Suwon-si (KR)
- (73) Assignee: SAMSUNG ELECTRONICS CO., LTD., Gyeonggi-Do (KR)
- () Term: 15 Years
- (21) Appl. No.: 29/886,946
- (22) Filed: Mar. 15, 2023

(30) Foreign Application Priority Data

- Nov. 29, 2022 (KR) 30-2022-0049808

(57) CLAIM

The ornamental design for an oven, as shown and described.

DESCRIPTION

FIG. 1 is a front perspective view of an oven showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is another front perspective view thereof in an alternate position;

FIG. 9 is an enlarged view of the encircled 9 in FIG. 1; and,

FIG. 10 is an enlarged view of the encircled 10 in FIG. 8. The even-dash broken lines illustrating portions of the oven form no part of the claimed design. The dot-dash broken lines encircling enlargement portions of the claimed design form no part of the claimed design.

1 Claim, 10 Drawing Sheets
